UNITED STATES PATENT OFFICE

101,153

DESIGN FOR A PLATE OR SIMILAR ARTICLE

George Wesp, New York, N. Y., assignor to Continental Ceramics Corporation, New York, N. Y., a corporation of New York

Application January 6, 1936, Serial No. 60,444

Term of patent 3½ years

To all whom it may concern:

Be it known that I, George Wesp, a citizen of the United States, residing in New York, Queens County, State of New York, have invented a new, original, and ornamental Design for a Plate or Similar Article, of which the following is a specification, reference being had to the accompanying drawing forming a part thereof.

The single figure in the drawing is a top plan view of a plate, showing between the dot and dash lines one repeat of the decorative border design which is repeated at regular intervals around the rim of the plate, and showing also the decorative center design.

The border design consists essentially of prominent leaf and floral sprays, there being two, similar but somewhat different designs of the same in each repeat, connected together by extremely slender and attenuated foliated lines of minute leaves and stems and the large decorative designs spread over from the border into the bowl of the plate toward the decorative center design as shown.

I claim:

The ornamental design for a plate or similar article as shown and described.

GEORGE WESP.
